CHIMNEY CONSTRUCTION AND
FITTING THEREFOR

Daniel Verne Meiller, Maywood, J. Donald Preble,
La Grange, and Loren W. Tuttle, Mount Prospect, Ill.

Application May 9, 1945, Serial No. 592,738

6 Claims. (Cl. 72—94)

1

This invention relates to chimney construction, and has to do with means for supporting a liner within a chimney while permitting ready access to the liner for inspection and for drainage of condensates therefrom.

The flue gases from gas burning equipment, such as space heaters and water heaters, contain large amounts of moisture as well as carbon dioxide or carbonic acid gas, which are apt to attack and cause rapid deterioration of the chimney receiving such gases, unless that is guarded against by means of a suitable liner. In the case of the chimney originally constructed to receive gases from equipment burning fuel other than gas, such as solid fuel, it usually is necessary to use a metal liner for the chimney, which liner should be constructed of stainless steel or equivalent metal resistant to the flue gases, when converting to gas fired equipment. When the chimney is originally built for use with gas fired equipment, a liner of vitrified clay, formed in pipe lengths or sections, is used. It is of importance that means be provided whereby the condensate from the combustion gases can readily be drained off from the liner, and whereby the interior of the liner may be inspected to assure that it is in a safe condition. It is, of course, important that inspection of the liner be had without necessity for tearing out any permanent part of the structure, and that the drainage means be also readily accessible for inspection and replacement if necessary.

Our invention is directed to a chimney construction particularly suitable for converting chimneys originally constructed for use with fuels other than gas, such as solid fuel, for use with gas fired equipment, while also being well suited for constructing chimneys originally intended for use with gas fired equipment. An important feature of our invention is the provision of a fitting, in the nature of a breaching box, which is mounted in the chimney and provides a support, in whole or in part, for the chimney liner, while giving ready access thereto for inspection and rendering possible effective drainage from the fitting of the condensate from the products of combustion passing through the liner. A further feature of our invention of practical importance is the provision of drainage means, the parts of which are spaced outward of the chimney so as to be readily accessible for inspection and repair, while guarding such parts against objectionable corrosion.

Further objects and advantages of our invention will appear from the detail description.

2

In the drawings:

Figure 1 is a fragmentary view, partly in elevation and partly broken away and in section, of a chimney construction embodying our invention;

5 Figure 2 is an outer end view, on an enlarged scale, of the liner supporting fitting, this view being taken substantially on line 2—2 of Figure 1;

10 Figure 3 is a fragmentary sectional view, on an enlarged scale, taken substantially on line 3—3 of Figure 1;

15 Figure 4 is a fragmentary vertical sectional view of a chimney construction embodying our invention in modified form as applied to a chimney originally constructed for use with gas fired equipment;

Figure 5 is a sectional view taken substantially on line 5—5 of Figure 4;

20 Figure 6 is a front view of the clean out fitting and the cover therefor of the chimney construction of Figures 4 and 5;

Figure 7 is a view similar to Figure 4 of a modified form of chimney originally constructed for use with gas fired equipment; and

25 Figure 8 is a sectional view taken substantially on line 8—8 of Figure 7.

In Figure 1 of the drawings, we have shown our invention as embodied in a construction comprising a chimney 10 formed of brick laid up with mortar in the usual manner, the lower portion of the chimney being located in the basement of the house or other building, underlying the first floor, including the joists 11 and flooring 12. The chimney 10 may be assumed to have been originally constructed for use with equipment burning fuel other than gas, such as hard fuel. In order to convert this chimney for use with gas burning equipment, it is necessary to place within the chimney a liner of stainless steel or equivalent material resistant to the combustion gases and moisture from the gas burning equipment. A liner 13, formed of suitable lengths of stainless steel tubing, is mounted within the chimney 10 and extends upward a suitable distance above the top of the chimney, the space between the upper end portion of the liner and the chimney cap being closed by suitable sealing compound, as is known and in accordance with usual practice. The lengths of the liner, one of which is shown at 14, are installed with their crimped or spigot ends down, the lower end portion of each liner section seating in the upper end portion of the next subjacent section and being secured thereto by screws 15, also of stainless

steel or equivalent material, or in any other suitable known manner. A bottom section 16 of the liner is provided with two tubular arms or sleeves 17 and 18 extending therefrom through the inner side of chimney 10, with sealing compound 19 surrounding each arm. The arm 17 is intended for connection to a gas fired water heater, and the arm 18 is intended for connection to the outlet flue of a furnace or space heater burning gas as the fuel therefor. The lower end of liner section 16 seats against a neck 20 of a box-like fitting 21 mounted in the chimney 10 so as to be firmly supported thereby. The fitting 21 provides a support for the liner 13, and carries the weight of the latter, in substantial part or in whole.

The fitting 21, like the liner 13, is constructed of stainless steel or equivalent material. It is of box-like construction, as will be clear from Figures 1, 2, and 3 of the drawings, and is of a length to extend outward of the chimney beyond the inner face thereof, as shown in Figure 1. Fitting 21 is open at its outer end, and is there provided with outwardly extending side flanges 22, an upwardly extending top flange 24 and a downwardly extending bottom flange 25. A short distance from its outer end the fitting is provided with a transverse wall or dam 26 extending from its lower wall, to which the dam 26 may be secured by soldering, welding, or in any other suitable manner. A drainage nipple 27 is secured in the bottom wall 28 of fitting 21, through which it opens a short distance inward of the fitting from dam 26 for the purpose of draining condensate therefrom. Nipple 27 is intended for reception of a tube 29 which may lead to the sewer or other suitable outlet.

Normally, the outer end of fitting 21 is closed by a flat cover 30, also formed of stainless steel, provided at its sides with channel elements 31 which slidably receive flanges 22, and, at its top, with a channel element 32 which receives flange 25 and, in cooperation therewith, limits downward movement of cover 30 relative to fitting 21. Cover 30 is provided, at its lower edge, with an outwardly projecting flange 33 providing a grip or handle which facilitates removal of and replacement of the cover 30. When cover 30 is removed from fitting 21, ready access is had to the interior of the fitting for clean out purposes, and this fitting also gives ready access to the interior of the liner 13 for inspection purposes. The fitting 21 also serves to collect the condensate from the products of combustion passing through the liner 13, which condensate is discharged through the nipple 27 and tube 29, it being noted that both nipple 27 and tube 29 are spaced an appreciable distance away from the chimney 10, thereby avoiding corrosion of these members such as would occur were they in contact with the chimney. It will also be noted that the nipple 27 and tube 29 are readily accessible for inspection and for repair or replacement, as may be required.

In the construction shown in Figures 4 and 5, the chimney 10a is originally constructed for use in connection with gas fired equipment. This chimney has mounted therein a liner 35 formed of suitable lengths of vitrified clay or like material, each length being provided with a bell at its upper end in which seats the lower end of the next superjacent section or length. The lowermost length 36 of liner 35 is provided with a tubular extension or arm 37 opening through the inner side of the chimney, with a suitable sealing compound 38 providing a seal between this

arm and the inner wall of the chimney. Arm 37 is intended for connection to the flue outlet of a gas fired space heater, such as a furnace. It will be understood that the lowermost liner section 36 may also be provided with an arm for connection to the outlet of a gas fired water heater or other gas fired equipment.

A fitting 39, preferably formed of cast iron, of cubiform or boxlike formation, is suitably supported in chimney 10a, and has mounted through its top wall a spud 40, with a sealing compound 41 providing a seat therefor and a seal thereabout, the upper portion of this spud being formed to provide a bell 42 in which seats the lower end portion of lining section 36, a suitable sealing compound 43 providing a tight seal between section 36 and bell 42. The fitting 39 is in free communication with the liner 35, and provides a support therefor, in whole or in substantial part.

Fitting 39 extends outward of the chimney 10a from liner 35, and is open at its outer end, the inner wall of the chimney being provided with a passage 45 extending therethrough from the outer end of fitting 39 opening freely thereinto. A condensate receiving pan 46, formed of stainless steel or other suitable material resistant to the gases flowing through the liner 35 and to the condensate from such gases or products of combustion, is supported within fitting 39 on inclined shoulders 47 at the sides thereof. This pan is inclined downward and outward of fitting 39 and is provided, at its outer end, with inwardly converging walls 48 merging into a spout 49. A tube 50, formed of stainless steel or other suitable material, receives the forward or outer portion of spout 49 from which it leads, at a downward and outward inclination, for discharging the condensate from pan 46.

A clean out fitting 51, in the form of an open frame constructed of cast iron, is mounted in the outer portion of passage 45 with a suitable sealing compound 52 providing a tight seal thereabout. Fitting 51 is provided, in the bottom wall thereof, with a rectangular opening which receives a drainage sump or basin 53, formed of stainless steel and provided at its top with a peripheral flange 54 seating on the top face of the bottom wall or frame 51. Basin 53 has a depending nipple 55 adapted to receive a drain tube leading to a sewer or other suitable point of discharge. The clean out fitting 51 is provided with a removable cover 56 held in closed position in any suitable manner. Conveniently, the cover 56 is provided with outwardly projecting studs 57 at the sides thereof, disposed for engagement with suitably formed lugs 58 formed integrally with fitting 51 at the sides of the opening thereof, lugs 58 defining with the side elements of fitting 51 upwardly opening slots or recesses which receive the studs 57 and cooperate therewith by a camming action for maintaining the door tightly seated on the outer face of fitting 51.

It will be seen that the fitting 39 provides a support for the liner 35 and, in conjunction with pan 46 and tube 50, collects the condensate from the products of combustion passing through liner 36, and discharges this condensate into basin 53, into which tube 50 discharges as shown, from which the condensate is discharged to the sewer or other suitable point of disposal. The clean out fitting 51 and its door 56 normally close the fitting 39 to the exterior of chimney 10a, while permitting ready access thereto for clean out, inspection of

the liner and replacement or repair of pan 46, tube 50, and basin 53, as required.

In Figure 7, as in Figure 4, the chimney 10a is assumed to have been originally constructed for use with gas fired equipment, and is provided with a liner 35 of vitrified clay having a tubular extension or sleeve 37 for connection to the flue of a gas fired furnace or space heater. The lowermost section 36 of liner 35 seats, at its lower end, in a neck 60 extending upwardly from the top wall of a fitting 61 suitably mounted in the lower portion of chimney 10a, a tight seal being formed between the neck and the end portion of liner section 36 by a suitable sealing compound 62. The fitting 61 is formed of vitrified clay and is provided, at its end adjacent passage 45 in chimney 10, with a reduced neck 63. A sealing compound 64 closes the space between neck 63 and the inner wall of the chimney for the major circumference of the neck, the lower portion of which overlies the inner end of a trough 66, also formed of vitrified clay, extending at inclination downward and outward from neck 63 to basin 53. It will be seen that by removing door 56 the fitting 61 and passage 45 may readily be cleaned out, and ready access is had to the liner 35 for inspection of the interior thereof. Nipple 55 of basin 53 is intended for reception of a tube leading to a sewer or other suitable point of discharge, as before.

While we have referred to the lowermost section 36 of the liner 35 of Figures 4 and 7, and the lowermost section 16 of the liner of Figure 1, as provided with extensions for connection to gas fired equipment and as seating in elements of the inspection and drain fitting, for purposes of description, it will be understood that the elements of the lining for connection to the gas fired equipment may be carried by any suitable one of the sections of the liner other than the lowermost thereof, the inspection and drain fittings in any case providing a support for the liner, either in whole or in part, while permitting ready access thereto for inspection purposes, and also providing means for draining off the condensate and cleaning out the fitting and, in the case of original installations, the passage in the chimney leading from the fitting. It will be understood, as above indicated, that changes in construction and arrangement of parts of our invention may be resorted to without departing from the field and scope thereof, and we intend to include all such variations, as fall within the scope of the appended claims, in this application, in which the preferred forms only of our invention have been disclosed.

We claim:

1. In chimney construction, a chimney, a fitting therein, a liner within said chimney opening at its lower end into said fitting, the latter and said chimney having clean out means giving access to the interior of said fitting through a side wall of said chimney, and condensate drainage means exterior of said chimney alongside said wall thereof with its upper end accessible through said clean out means and communicating with said fitting for receiving condensate therefrom.

2. In chimney construction, a chimney, a fitting therein, a liner within said chimney opening at its lower end into said fitting, the latter and said chimney having clean out means giving access to the interior of said fitting through a side wall of said chimney, and condensate drainage means

comprising a drain tube exterior of said chimney extending alongside side of but spaced from said wall with its upper end accessible through said clean out means and communicating with said fitting for receiving condensate therefrom.

3. In chimney construction, a chimney, a fitting therein projecting outward beyond a side of said chimney, a liner within said chimney opening at its lower end through the top of said fitting, the latter having a clean out opening at its outer end and a removable closure therefor, and condensate drainage means exterior of said chimney adjacent said side thereof opening at its upper end into said fitting adjacent its outer end.

4. In chimney construction, a chimney, an inspection and drain fitting therein, a liner within said chimney opening at its lower end through the top wall of said fitting, said chimney having a passage opening at its inner end into said fitting and at its outer end through a side wall of said chimney, a clean out fitting at the outer end of said passage projecting outward beyond said chimney and having a removable closure, a drain tube extending from the bottom of said clean out fitting exterior of said chimney, and means for delivering condensate from said inspection and drain fitting to said tube.

5. In chimney construction, a chimney, an inspection and drain fitting therein, a liner within said chimney opening at its lower end through the top wall of said fitting, said chimney having a passage opening at its inner end into said fitting and at its outer end through a side wall of said chimney, a clean out fitting at the outer end of said passage projecting outward beyond said chimney and having a removable closure, a removable drainage basin carried by said clean out fitting at the bottom thereof, a drain tube extending from said basin exterior of and spaced from said chimney, and means for delivering condensate from said inspection and drain fitting to said basin.

6. A combination flue-liner drain and inspection unit comprising an angular tubular member having one end thereof adapted for telescopic attachment to a flue liner and the other end projecting outwardly and downwardly exteriorly of said flue, a closure plate removably secured to said other end of said member to permit inspection of said flue liner when said plate is removed, means in said member below said plate to receive condensation from said tubular member, and a connection to said means for the attachment of a drain pipe.
